WASHBOARD

Thomas Glen, Jr., Coogee, New South Wales,
AustraliaApplication May 11, 1932, Serial No. 610,547, and
in Australia March 2, 1932

1 Claim. (Cl. 68—29)

The invention relates to washing boards of the class usually provided with a corrugated rubbing surface and a head board upon which the block of soap employed in the laundering is intended to rest.

According to my invention a head plate at the top of the board has an aperture corresponding in shape with a block of soap which rests upon a fixed back.

10 The head plate is preferably of sheet metal and is adapted to be pressed down against the action of springs located between it and the back of the board. The article being washed is passed over the head plate with sufficient pressure to

15 depress and present the surface of the soap to the article.

At the sides and ends of the aperture are downwardly projecting guide lugs which maintain the soap in position and which pass through corresponding perforations in the back of the board thereby permitting the head plate to closely approach the back when the soap is nearly consumed.

20 A mode of carrying my invention into practical effect is illustrated in the accompanying drawing wherein:—

Fig. 1 is a perspective view,

Fig. 2 a side sectional elevation taken on line 2—2 of Figure 1, and

30 Fig. 3 a sectional plan on 3—3 Fig. 1.

The head plate 1 is slidable in the side members 2. A washing board having a rubbing surface 3 and has an aperture 4 corresponding with a rectangular block of soap which rests upon a back 5 fixed to the board.

At the sides and ends of the aperture are comparatively wide projecting guide lugs 6 which maintain the soap in position and which slide through corresponding perforations in the back 5 fixed to the side members at the rear of the 60 head plate.

Bow springs 7 are secured at 8 to the head plate one upon each side of the aperture therein and, bearing at their ends upon back 5, tend to push the head plate away from the back so 65 that the surface of the soap is normally below the surface of the head plate which is pressed downwardly when it is desired to apply soap to an article.

Some of the guide lugs extend from the lower 70 edge of the aperture and the soap may be supported by them as well as by the back.

I claim:—

In a washboard having a frame and a rubbing surface, said frame comprising a top and side 75 members, a head plate extending between said top and said rubbing surface and slideable in said side members, guide lugs integral with the head plate and projecting rearwardly from the edges of an aperture formed in said head plate, a 80 back fixed to said side members at the rear of said head plate, some of said guide lugs extending from the lower edge of the aperture upon which soap may be supported as well as upon said back, the back having perforations through 85 which the guide lugs slide, and springs interposed said head plate and said back as specified.

THOMAS GLEN (JUNIOR).
